LACE MACHINE

Adam F. Schuler, Gouverneur, N. Y.; Paul Krasley, executor of said Adam F. Schuler, deceased, assignor to Chester Lace Mills, Chester, Pa., a corporation of Pennsylvania

Application August 10, 1943, Serial No. 498,103

15 Claims. (Cl. 87—14)

This invention relates to an attachment for a lace-making machine, for controlling, manipulating, grouping and holding predetermined warp and weft threads in predetermined relation to each other, during the weaving of a lace or net fabric on the machine, for passage of the shuttle threads between the prearranged warps and wefts and around certain of these threads to complete the fabric.

The attachment of the present invention is particularly adapted to the manufacture of net fabrics in accordance with the disclosure of my copending application Serial No. 478,848, filed March 11, 1943.

The construction and operation of the attachment of the present invention will be fully disclosed hereinafter, reference being had to the accompanying drawings of which:

Fig. 1 is a front elevation of sufficient of a lace-making machine to illustrate the application of the attachment of the present invention thereto;

Fig. 2 is a transverse sectional elevational taken on the line 2—2 of Fig. 1;

Fig. 3 is an end elevation of a portion of the lace machine showing the attachment of the present invention applied thereto, as viewed from the plane 3—3, Fig. 1;

Fig. 4 is a transverse sectional elevation taken on the line 4—4, Fig. 1;

Fig. 5 is a fragmentary plan view, as viewed from the plane 5—5, Fig. 4;

Fig. 6 is a detached perspective view of the attachment partly in section;

Fig. 7 is a rear elevation of the attachment looking in the direction of the arrow a, Fig. 6;

Fig. 8 is a sectional plan view of the attachment taken on the line 8—8, Fig. 7;

Figs. 9, 10, 11, 12, 13 and 14 are diagrammatic plan views, similar to Fig. 8, showing the elements in different positions;

Fig. 15 is a diagrammatic view of a swatch of the fabric; and

Figs. 16 and 17 illustrate fragments of the thread-controlling bars of the machine.

As shown in Figs. 1 and 2, the machine comprises a plurality of transversely extending frame members 1, 1, certain of which are provided with brackets 2 for supporting a fabric take-off roll 3 and a fabric take-up roll 4. The fabric Z extends from the take-off roll 3 downwardly over a work-bar 5 which is supported by brackets 6 on intermediate frame members 1.

From the lower edge 7 of the work-bar 5, adjacent which the fabric Z is formed, the warp

threads v and w of the fabric extend downwardly to warp beams V and W respectively, which are located adjacent the base line of the machine, at the opposite sides respectively of the longitudinal central vertical plane of the machine. Extending downwardly from the lower edge 7 of the work-bar 5, intermediate the diverging warp threads v and w, are weft or spool threads x and y. The spool threads x and y pass around a guide bar 8, located adjacent the base line of the machine, to a creel 9 located at the back of the machine and on which are mounted the spools 10, 10. Also extending from the point of weaving adjacent the edge 7 of the work-bar 5, are shuttle threads s which pass to bobbins S carried by the oscillating shuttles 12 of the machine.

Lingoes 11 are suspended on the weft threads x and y to apply the necessary tension thereto. Any suitable conventional means may be provided for braking the rotation of the warp beams V and W to apply the necessary tension to the warp threads v and w.

The shuttles 12 are adapted to slide in arcuate grooves formed in shuttle guide bars 13 and 14, between which the warp and weft threads v, w, x, and y extend, said shuttle guide bars being rigidly secured to the frame members 1, 1 and extending longitudinally of the machine.

The warp threads v and w and the weft threads x and y, pass through eyes 15, 15 formed on or carried by thread bars 16, 17, 18 and 19 respectively, as clearly shown in Fig. 16. These thread bars extend longitudinally of the machine and are slidably mounted in guides 20 secured to the frame members 1.

Relative shifting of the threads v, w, x and y, to produce a pattern, is effected by mechanism hereinafter described. After each shifting of the threads with respect to each other, by the bars 16, 17, 18 and 19, the threads are combed and held in vertical parallel laterally spaced relation for the passage of the shuttles 12, by means of comb bars 21 and 22. After shifting of the bars 16, 17, 18 and 19, the combs 21 and 22 are adapted to enter the hanging warps and wefts at a point well below the lower edge 7 of the work-bar 5, and to move upwardly while in contact with the hanging threads to a point adjacent lower edge 7 of the work-bar 5.

The comb bars 21 and 22 operate alternately, and their motions are controlled by cams 23 and 24, on a cam shaft 25, and 26 and 27, on a cam shaft 28. The cam shafts 25 and 28 are rotatably mounted on the frame members 1, and are rotated

in unison by intermeshing gears 29 and 30, respectively secured to the cam shafts 25 and 28.

The oscillations of the shuttle 12 through the hanging warp and weft threads are effected by hook bars 31 and 32, which, in turn, are actuated by a crank 33 on a longitudinal shaft 34, which latter is provided with a gear 35 intermeshing with the gear 29 on the cam shaft 25.

The warp threads *v* and *w* are adapted to be shifted laterally, in opposite directions simultaneously, to an extent equal to the lateral spacing of the shuttles 12. The warp threads *v* and *w* are moved in opposite directions respectively, by the bars 16 and 17, for passage of the shuttles 12 from the back shuttle guide bar 13 to the front shuttle guide bar 14, to carry the shuttle threads *s* to one side of the separated warp threads, whereupon, the warp-controlling bars 16 and 17 are respectively shifted reversely for passage of the shuttles 12 from the front shuttle guide bar 14 to the back shuttle guide bar 13, to carry the shuttle threads *s* around in front of the warps, to the opposite sides thereof, and back of said warps.

Successive repeats of the lateral shifting or shogging of the warp threads *v* and *w* and the oscillations of the shuttles 12, through the warp threads, effects twisting or wrapping of the shuttle threads *s* around the warp threads *v* and *w* respectively.

The longitudinal shifting of the warp control bars 16 and 17 is effected by levers 36 and 37, which are pivotally mounted on a common shaft 38 extending transversely of the machine and provided with cam followers 39 and 40. The cam followers 39 and 40 engage shogging cams 41 and 42 on the cam shafts 25 and 28 respectively, said engagement being maintained by springs 41a and 42a (Fig. 9).

The mechanism, so far described is common to a conventional lace making machine, such for example as that shown in prior patent to Joseph H. Bromley, Jr., #1,066,789, dated July 8, 1913. For the purpose of clarity the jacks, the jack-controlling mechanism, and the jacquard mechanism have been eliminated from the present drawings, although it will be understood that these mechanisms may be operated in whole or in part in conjunction with the mechanism of the present invention, if desired, for producing certain patterns in fabrics woven on the loom.

The present invention is particularly directed to an attachment for shifting the weft or spool thread controlling bars 18 and 19, to produce a net fabric, such as that disclosed in the aforesaid copending application Serial No. 478,848, filed March 11, 1943.

The attachment is shown particularly in Figs. 6, 7 and 8 of the drawings. As shown in the swatch illustrated diagrammatically in Fig. 15, each of the weft threads *x* is adapted to pass between a pair of warp threads *v*, *v*, and each of the weft threads *y* is adapted to pass between a pair of the warp threads *w*, *w*, at relatively spaced intervals longitudinally of the warp threads *v*, *v* and *w*, *w*, with the pairs of warp threads in each instance bound together intermediate the points where the weft threads pass between the adjacently disposed warp threads, by a predetermined number of wrappings of the shuttle threads *s*.

At relatively spaced intervals, the weft threads *x* and the weft threads *y* extend from the wales of the fabric in which these wefts are respectively bound for the greater part of their lengths, into

the wales lying immediately adjacent thereto, to be bound in the receiving wales by a predetermined number of twists of the shuttle threads around the pairs of warp threads in the respective receiving wales, after which the weft threads *x* and *y* again return to the wales of their respective origins.

Each of the warp threads *x* alternately travels from its wale of origin to the wale lying immediately to the left thereof, then back into its wale of origin, then into the wale lying immediately to the right thereof, after which it returns to its wale of origin. Each of the weft threads *y* similarly extends from its wale of origin into the wales lying immediately to the right and left thereof, alternately, said wefts *x* and *y* crossing each other at each of the deviations thereof. This alternate staggered tying of the adjacent wales together produces the net fabric shown in the aforesaid pending application.

In order to effect the shifting of the weft threads to the right and to the left of their wales of origin, and in order to effect tying of the weft threads in the wales to which they are periodically attached, four lateral positions of each thread is required; and in order to effect the shifting of each of the threads to each of its required positions, the bars 18 and 19, which respectively control the weft threads *x* and *y*, are required to be held in each of the four different positions for a predetermined length of time while the shuttles 12 are making the required number of wrappings of the shuttle threads *s* around the pairs of warp threads *v* and *w* between which the weft threads *x* and *y* respectively pass.

As shown in Figs. 6, 7 and 8, movements of the thread bars 18 and 19 are controlled by carriages 50 and 80 respectively. The carriages 50 and 80 are adapted to slide horizontally in a bracket 43 secured to the end frame 1 of the machine. The carriages 50 and 80 are adapted to be moved in opposite directions, simultaneously, by levers 51 and 81 respectively, said levers being pivotally mounted on a common shaft 44 which is secured in the bracket 43.

The levers 51 and 81 are provided with cam followers 52 and 82 respectively, which are held in contact with the peripheries of cams 53 and 83 respectively by springs 54 and 84 respectively. The cams 53 and 83 are secured to a common transverse shaft 45 which is provided with a gear 46. The gear 46 meshes with a pinion 47 on the cam shaft 28. As the shaft 45 is rotated, the levers 51 and 81 are simultaneously rocked in opposite directions and caused to dwell, for predetermined periods of time, by the cams 53 and 83 on said shaft 45. Such rocking and dwelling of levers 51 and 81 effects corresponding longitudinal movements, in opposite directions simultaneously, of the carriages 50 and 80, and a corresponding dwell in the movements thereof.

The carriages 50 and 80 are provided with guide boxes 55 and 85 respectively, in which are vertically, slidably mounted two series of bar-positioning elements 55x, 55y and 85x, 85y respectively, which are adapted to be dropped between a stop 55a on the carriage 50 and stops 18a and 19a on the bars 18 and 19 respectively, and between a stop 85b on the carriage 80 and stops 18b and 19b on the bars 18 and 19 respectively, for controlling the positions of the thread-bars 18 and 19.

As shown in Fig. 6, the series 55x includes three droppers x1, x2, x3, the series 55y includes three droppers y1, y2, y3, the series 85x includes

three droppers x_4 , x_5 , x_6 , and, the series $85y$ includes three droppers y_4 , y_5 , y_6 .

As shown in Fig. 15, the weft threads x are adapted to be moved into, and to hang in, four different vertical positions, indicated at $1x$, $2x$, $3x$ and $4x$ during successive stages respectively of the weaving of the fabric; and the weft threads y are adapted to be moved into, and hang in, four different vertical positions $1y$, $2y$, $3y$, and $4y$, while the shuttle threads s is given a predetermined number of twists around the pairs of adjacent warp threads v , v and w , w , with which the weft threads x and y are respectively associated throughout the greater portions of the lengths of the wales of the fabric formed thereby.

Starting with that portion of the fabric at and adjacent the line A—A, Fig. 15, the weft threads x are held in the position indicated by the short vertical broken line $3x$, while a shuttle thread s makes a predetermined number of wraps around the two warp threads v , v ; and the weft threads y are held in the position indicated by the short vertical broken line $2y$ while a shuttle thread s makes three wraps around the two warp threads w , w .

In order to effect this above noted holding of the weft threads x and y , two droppers x_1 and x_2 are in position between the stop $55a$ on the carriage 50 and the stop $18a$ on the bar 18 ; and one dropper y_1 is in position between the stop $55a$ on the carriage 50 and the stop $19a$ on the bar 19 , as indicated in Fig. 9, these droppers having been placed in position adjacent to stop $55a$, prior to the carriage 50 being moved to the right, as shown in Fig. 9, to effect the aforesaid positioning of the weft threads x and y respectively.

The lowering and raising of the various droppers into and out of position between the stops $55a$ and $85b$, on the carriages 50 and 80 and the stops $18a$, $19a$, $18b$ and $19b$ on the bars 18 and 19 , are effected by ordinary jacquard mechanism associated with the loom, as will be hereinafter described.

It will be noted in Fig. 9 that, while the carriage 50 is holding the thread bars 18 and 19 in the positions above noted, the stops $18b$ and $19b$ are spaced a considerable distance from the stop $85b$ on the carriage 80 , which has been moved to the left simultaneously with the shift to the right of the carriage 50 to afford free movement of the desired droppers between said stops.

While the mechanism is set up for holding the threads x and y during the making of the portion of the fabric adjacent the line A—A, the jacquard mechanism effects setting up of the proper arrangement of droppers between the stop $85b$ on the carriage 80 and the stops $18b$ and $19b$ on the bars 18 and 19 , for shifting the threads x and y to produce the portion of the fabric adjacent the line B—B of Fig. 15, with one dropper x_4 placed in position between the stop $85b$ of the carriage 80 and the stop $18b$ on the bar 18 , and two droppers y_4 and y_5 placed in position between the stop $85b$ on the carriage 80 and the stop $19b$ on the bar 19 .

The position of the carriages 50 and 80 is then reversed from those shown in Fig. 9 to those shown in Fig. 10, the carriage 50 moving to the left simultaneously with the moving of the carriage 80 to the right. The droppers y_4 and y_5 , being in position adjacent the stop $85b$ of the carriage 80 , engage the stop $19b$ on the bar 19 and move the weft threads y to the position indicated at $3y$; and the dropper x_4 , being in position between the stop $85b$ of the carriage 80 and the

stop $18b$ on the bar 18 , move the weft threads x to the position indicated at $2x$. The threads x and y now hang in vertical positions corresponding to the line $2x$ and $3y$ respectively, while the shuttle threads s make a number of wraps around the pairs of warps v , v and w , w respectively.

While the carriages 50 and 80 are in the position shown in Fig. 10, effecting a holding of the threads x and y in the positions $2x$ and $3y$ respectively, the jacquard mechanism is effecting a setting up of the droppers for positioning the threads x and y for making that portion of the fabric shown adjacent the line C—C, wherein each weft thread x moves from its wale of origin with the warps v , v across the space between that and the next adjacent wale and passes between the warps w , w of said next adjacent wale which, in this instance, lies to the left of the wale of origin of the weft x ; and the weft threads y pass from their respective wales of origin with the warps w , w across said space and between the warps v , v of the next adjacent wale to the right.

The threads x and y are then respectively held in the positions indicated by the lines $1x$ and $4y$, while the shuttle threads s make a predetermined number of turns around the pairs of warps v , v and w , w respectively. The setup of the droppers for position C—C includes droppers y_1 , y_2 and y_3 between the stop $55a$ on the carriage 50 and the stop $19a$ on the bar 19 , and eliminates all of the droppers from between the stop $55a$, on the carriage 50 , and the stop $18a$ on the bar 18 , thus, when the carriages 50 and 80 change position by shifting from the right to the left and vice versa, from Fig. 10 to Fig. 11, the shifting of the threads x and y as noted, is effected.

While the carriages 50 and 80 are holding the threads x and y in position C—C, as shown in Fig. 11, the jacquard mechanism is making the proper set up of droppers between the stop $85b$ on the carriage 80 , the stop $18b$ on the bar 18 , and the stop $19b$ on the bar 19 , for positioning the threads x and y for the weaving of that portion of the fabric adjacent the line D—D (Fig. 15). This set up (Fig. 12) is the same as the set up (Fig. 9) for the area of the fabric B—B (Fig. 15).

The set up for the area adjacent the line E—E is the same as that for the area A—A; the set up for F—F is the same as the set up for B—B and D—D; the set up for G—G is the same as A—A and E—E; the set up for H—H is the same as the set up for B—B, D—D, and F—F; and the set up I—I is the same as A—A, E—E, and G—G.

The set up for J—J changes (see Fig. 13), the weft threads y move to position $1y$ (Fig. 15) and the weft threads x move to position $4x$ (Fig. 15), with all droppers y_4 , y_5 , and y_6 removed from between the stop $85b$ in the carriage 80 and the stop $19b$ on the thread bar 19 ; and with all three droppers x_4 , x_5 , and x_6 in place between the stop $85b$ on the carriage 80 and the stop $18b$ on the thread bar 18 . After this set up is made as in Fig. 13, the carriages 50 and 80 reverse positions right to left and left to right respectively, as shown in Fig. 14, wherein the threads x and y are held in their extreme positions x_4 and y_1 respectively (Fig. 15) while the shuttle threads s , s make a predetermined number of wraps around the pairs of warp threads v , v and w , w respectively.

At J—J it will be noted, the weft threads x and y move outwardly, in opposite directions, from their respective wales of origin into the

wales of the fabric next adjacent thereto, left and right, and then return to their wales of origin through area K—K, the set up for which is the same as A—A, E—E, G—G and I—I, to area L—L wherein the weft threads x and y , occupy inside positions $2x$ and $3y$ respectively. The thread holding set up of the droppers for L—L corresponds to the set up for area F—F, for example.

The different set ups for the areas A—A to L—L respectively are repeated in regular succession throughout the length of the fabric, in each adjacent pair of wales, and the interconnecting of the adjacent wales, as in the areas C—C and J—J, in staggered relation, tie the various strand-forming wales of the fabric together to form the open meshes of the net.

Each of the droppers $1x$, $2x$, $3x$, $4x$, $5x$, $6x$, $1y$, $2y$, $3y$, $4y$, $5y$, and $6y$ is connected by a wire 10 to a harness cord 11 , said wire passing through an opening 72 formed in a laterally extending plate 73 secured to and forming part of the carriage 50 or 80 , as the case may be. A spring 74 confined between the under side of the plate 73 and a collar 75 on each wire 10 at all times tends to force the respective droppers downwardly between the stops $55a$ or $85b$ on the carriages 50 , 80 and the stops $18a$, $18b$, $19a$, $19b$ on the thread controlling bars 18 and 19 or into a position of rest on top of the bar stops $18a$, $18b$, $19a$, $19b$.

The droppers are raised out of operative position by a vertical pull on the harness cords 11 which are connected to needles of the jacquard mechanism of the loom, which, being of ordinary construction and operating in a conventional manner, have not been shown in the drawings of the present case.

The jacquard mechanism of the loom operates to raise the droppers $x1$, $x2$ and $x3$, of the group $55x$, and the droppers $y1$, $y2$, and $y3$, of the group $55y$, when the carriage 50 is in its extreme position to the left, as viewed in Figs. 8 to 14; and to raise the droppers $x4$, $x5$ and $x6$, of the group $85x$, and $y4$, $y5$ and $y6$ of group $85y$, when the carriage 80 is in its extreme position to the right, as viewed in said figures.

The cards of the jacquard mechanism are punched in a manner to cause the jacquard mechanism to hold all the droppers in elevated position, which are not required, until the carriages 50 and 80 shift to their other extreme positions respectively, and to cause the jacquard mechanism to lower into operative position, before such shifting of the carriages, only those of the droppers which are required.

I claim:

1. An attachment for a lace loom employing a plurality of longitudinally shiftable thread controlling bars, said attachment comprising means for shifting at least one of the bars to variable extents lengthwise thereof, said means including a carriage uniformly reciprocable parallel to said bars, and means for varying the longitudinal relationship between the carriage and the variable bar to effect variations in the positioning of the variable bar relative to the others of said bars by the uniform reciprocation of the carriage.

2. An attachment for a lace loom employing a plurality of longitudinally shiftable thread controlling bars, said attachment comprising means for shifting at least one of the bars to variable extents lengthwise thereof, said means including a carriage uniformly reciprocable parallel to said bars, and variable means mounted on the car-

riage for reciprocation therewith to vary the longitudinal relationship between the carriage and the variable bar to effect variations in the positioning of the variable bar relative to the others of said bars by the uniform reciprocations of the carriage.

3. An attachment for a lace loom employing a plurality of longitudinally shiftable thread controlling bars, said attachment comprising means for shifting at least one of the bars to variable extents lengthwise thereof, said means including a carriage uniformly reciprocable parallel to said bars, and variable spacer means adapted to be interposed between said carriage and said variable bar for effecting variations in the positioning of the variable bar relative to the others of said bars by the uniform reciprocations of the carriage.

4. An attachment for a lace loom employing a plurality of longitudinally shiftable thread controlling bars, said attachment comprising means for shifting at least one of the bars to variable extents lengthwise thereof, including a carriage reciprocable parallel to said bars, an abutment on each variably shiftable bar, an abutment on said carriage, and a plurality of spacer elements mounted on said carriage and adapted to be selectively moved transversely of said bars into and out of position intermediate said abutments.

5. An attachment for a lace loom employing a plurality of longitudinally shiftable thread controlling bars, said attachment comprising means for shifting at least one of the bars to variable extents lengthwise thereof, including a carriage reciprocable parallel to said bars, an abutment on each variably shiftable bar, an abutment on said carriage, a plurality of spacer elements mounted on said carriage and adapted to be selectively moved transversely of said bars into and out of position intermediate said abutments, and means for moving said carriage in one direction relative to said bars to spread said abutments apart for changing the number of spacers positioned therebetween.

6. An attachment for a lace loom employing a plurality of longitudinally shiftable thread controlling bars, said attachment comprising means for shifting at least one of the bars to variable extents lengthwise thereof, including a carriage reciprocable parallel to said bars, an abutment on each variably shiftable bar, an abutment on said carriage, a plurality of spacer elements mounted on said carriage and adapted to be selectively moved transversely of said bars into and out of position intermediate said abutments, means for moving said carriage in one direction relative to said bars to spread said abutments apart for changing the number of spacers positioned therebetween, and means for resiliently moving said bars in an opposite direction to close said abutments against the spacers interposed therebetween.

7. An attachment for a lace loom employing at least two longitudinally shiftable thread controlling bars, means for respectively shifting said bars to differently variable extents lengthwise thereof, including a pair of carriages reciprocable parallel to said bars, a pair of abutments on each variably shiftable bar, an abutment on each carriage, and a plurality of spacer elements mounted on each carriage and adapted to be selectively moved transversely of said bars into and out of position intermediate the abutments on the bars and carriages respectively.

8. An attachment for a lace loom employing

at least two longitudinally shiftable thread controlling bars, said attachment comprising means for respectively shifting said bars to differently variable extents lengthwise thereof, including a pair of carriages reciprocable parallel to said bars, a pair of abutments spaced apart at different location on each variably shiftable bar, an abutment on each carriage adapted to cooperate respectively with the relatively spaced abutments on the bars, a plurality of spacer elements mounted on each carriage and adapted to be selectively moved transversely of said bars into and out of position intermediate the abutments on the bars and carriages respectively, and means for moving said carriages in opposite directions relative to each other to spread the abutments on one of said carriages and at one location on said bars apart for changing the number of spacers positioned therebetween.

9. An attachment for a lace loom employing at least two longitudinally shiftable thread controlling bars, said attachment comprising means for respectively shifting said bars to differently variable extents lengthwise thereof, including a pair of carriages reciprocable parallel to said bars, a pair of abutments spaced apart at different locations on each variably shiftable bar, an abutment on each carriage adapted to cooperate respectively with the relatively spaced abutments on the bars, a plurality of spacer elements mounted on each carriage and adapted to be selectively moved transversely of said bars into and out of position intermediate the abutments on the bars and carriages respectively, means for moving said carriages in opposite directions relative to each other to spread the abutments on one of said carriages and at one location on said bars apart for changing the number of spacers positioned therebetween and close the abutment on the other carriage and the abutments at the other location on said bars against the number of spacers interposed therebetween during previous separation thereof.

10. An attachment for a lace loom employing at least two longitudinally shiftable thread controlling bars, said attachment comprising means for shifting said bars to differently variable extents lengthwise thereof, including a pair of carriages reciprocable parallel to said bars, a pair of abutments spaced apart at different locations on each variably shiftable bar, an abutment on each carriage adapted to cooperate respectively with the relatively spaced abutments on the bars, a plurality of spacer elements mounted on each carriage and adapted to be selectively moved transversely of said bars into and out of position intermediate the abutments on the bars and the abutments on the carriages, cam and follower means for moving said carriages in opposite directions relative to each other to spread said abutment on one of the carriages and the cooperating abutments on the bars apart for changing the number of spacers positioned therebetween, and resilient means for moving said bars in an opposite direction to close the abutments on the bars and carriages against the spacers interposed therebetween and to maintain contact between said cams and followers.

11. A lace loom comprising a plurality of horizontal longitudinally shiftable bars respectively controlling sets of vertically hanging threads, transversely reciprocable shuttles operable between adjacent hanging threads, means for shogging predetermined bars longitudinally to a constant predetermined extent to change the hang-

ing positions of the threads controlled thereby from side to side of the paths traversed by said shuttles to wrap shuttle-carried threads around the constant-change threads, and means for shogging other predetermined bars to variable predetermined extents to change the hanging positions of the threads controlled thereby with respect to the paths traversed by said shuttles and with respect to the hanging positions of said constant-change threads, the last said shogging means comprising a carriage reciprocable parallel to said bars, and means for changing the longitudinal relationship between the carriage and the variably movable bars during said reciprocation of the carriage.

12. A lace loom comprising a plurality of horizontal longitudinally shiftable bars respectively controlling sets of vertically hanging threads, transversely reciprocable shuttles operable between adjacent hanging threads, means for shogging predetermined bars longitudinally to a constant predetermined extent to change the hanging positions of the threads controlled thereby from side to side of the paths traversed by said shuttles to wrap shuttle-carried threads around the constant-change threads, and means for shogging other predetermined bars to variable predetermined extents to change the hanging positions of the threads controlled thereby with respect to the paths traversed by said shuttles and with respect to the hanging positions of said constant-change threads, the last said shogging means comprising an abutment on the variable bar, a carriage reciprocable parallel to said bars, an abutment on the carriage, and spacer elements mounted in the carriage and adapted to be interposed between said abutments.

13. A lace loom comprising a plurality of horizontal longitudinally shiftable bars respectively controlling sets of vertically hanging threads, transversely reciprocable shuttles operable between adjacent hanging threads, means for shogging predetermined bars longitudinally to a constant predetermined extent to change the hanging positions of the threads controlled thereby from side to side of the paths traversed by said shuttles to wrap shuttle-carried threads around the constant-change threads, and means for shogging other predetermined bars to variable predetermined extents to change the hanging positions of the threads controlled thereby with respect to the paths traversed by said shuttles and with respect to the hanging positions of said constant-change threads, the last said shogging means comprising a pair of carriages, means for simultaneously reciprocating said carriages parallel to said bars in opposite directions respectively, abutments on said carriages, longitudinally spaced abutments on each variable bar, and spacer elements mounted on said carriages and adapted to be interposed between the abutments on the carriages and the abutments on the bars.

14. A lace loom comprising a plurality of horizontal longitudinally shiftable bars respectively controlling sets of vertically hanging threads, transversely reciprocable shuttles operable between adjacent hanging threads, means for shogging predetermined bars longitudinally to a constant predetermined extent to change the hanging positions of the threads controlled thereby from side to side of the paths traversed by said shuttles to wrap shuttle-carried threads around the constant-change threads, and means for shogging other predetermined bars to variable predetermined extents to change the hanging po-

sitions of the threads controlled thereby with respect to the paths traversed by said shuttles and with respect to the hanging positions of said constant-change threads, the last said shogging means comprising a pair of carriages, means for simultaneously reciprocating said carriages parallel to said bars in opposite directions respectively, abutments on said carriages, longitudinally spaced abutments on each variable bar, spacer elements mounted on said carriages and adapted to be interposed between the abutments on the carriages and the abutments on the bars, and jacquard-controlled means for effecting changing of the number of interposed spacer elements effective in the carriages during each reciprocation thereof.

15. A lace loom comprising a pair of inside and a pair of outside horizontal longitudinally shiftable bars respectively controlling four sets of vertically hanging threads, transversely reciprocable shuttles operable between adjacent hanging threads, means for shogging the outside bars

longitudinally in opposite directions simultaneously to a constant predetermined extent to change the hanging positions of the threads controlled thereby from side to side of the paths traversed by said shuttles to wrap shuttle-carried threads around the constant-change threads, and means for shogging the inside bars to variable predetermined extents to change the hanging positions of the threads controlled thereby with respect to the paths traversed by said shuttles and with respect to the hanging positions of said constant-change threads, the last said means comprising a pair of carriages, means for simultaneously reciprocating said carriages parallel to said bars in opposite directions respectively, abutments on said carriages, abutments spaced apart along each of said inside bars, and a series of spacer elements on each carriage for each inside bar adapted to be selectively interposed between the abutments on the carriages and the abutments on said inside bars.

ADAM F. SCHULER.
